The ornamental design for a pressure cooker, as shown and described.

DESCRIPTION

FIG. 1 is a front perspective view of a pressure cooker showing my new design. The buttons and digital display of the front panel on the base of the pressure cooker are represented in broken lines.

FIG. 2 is a back perspective view of the pressure cooker shown in FIG. 1. The electrical socket at the bottom, the joint area in the back, and the air pore area right above the wave-shaped base are represented in broken lines.

FIG. 3 is a front view of the pressure cooker shown in FIG. 1. FIG. 4 is a back view of the pressure cooker shown in FIG. 1. FIG. 5 is a left side view of the pressure cooker shown in FIG. 1.

FIG. 6 is a right side view of the pressure cooker shown in FIG. 1.

FIG. 7 is a top view of the pressure cooker shown in FIG. 1; and,

FIG. 8 is a bottom view of the pressure cooker shown in FIG. 1. The bottom vents are represented in broken lines. The broken lines are for illustrative purpose only and form no part of the claimed design.
